(57) CLAIM

The ornamental design for a display screen or portion thereof with icon, as shown and described.

DESCRIPTION

FIG. 1 is a front view of a display screen or portion thereof with icon, showing my new design; and,
FIG. 2 is a front view of a display screen or portion thereof with icon showing a second embodiment of the new design.
The dash-dot broken line illustrated in the figures is included for the purpose of showing a display screen or portion thereof and forms no part of the claimed design.

1 Claim, 1 Drawing Sheet
